UNITED STATES PATENT OFFICE.

GEORGE C. PARKER, OF EXPO, VIRGINIA, ASSIGNOR OF ONE-THIRD TO D. J. ALEXANDER AND ONE-THIRD TO ALPHEUS FIELDS, BOTH OF NORFOLK, VIRGINIA.

METAL FOLDING SHIPPING-CASE.

1,369,704.

Specification of Letters Patent. Patented Feb. 22, 1921.

Application filed September 23, 1919. Serial No. 325,770.

To all whom it may concern:

Be it known that I, GEORGE C. PARKER, a citizen of the United States, residing at Expo, in the county of Norfolk, State of Virginia, have invented certain new and useful Improvements in Metal Folding Shipping-Cases; and I do hereby declare the following to be a full, clear, and exact description of the invention, such as will enable others skilled in the art to which it appertains to make and use the same.

This invention relates to folding shipping cases and while well adapted for the shipping of eggs, it will of course be understood that it may be employed in connection with any goods for which it is adapted.

The object of the invention is to provide a metallic shipping case that may be easily and quickly unfolded or set up and as readily folded or knocked down so as to occupy small space for shipment, a further object of the invention being to so construct the case as that it may be economical in the use of metal, may be cheap to manufacture, will be extremely durable and will be rigid when set up and ready for use.

In the drawings:

Figure 1 is a perspective view showing a case embodying the present invention, one side being swung outwardly to permit of folding of the ends and the partition, one of the ends being folded into the bottom pan.

Fig. 2 is a section taken transversely through the case set up, the section being staggered to include the openings of the closure members and to show the partition with its equipment in elevation.

Fig. 3 is a detail horizontal sectional view through one corner of the case.

Fig. 4 is a perspective view showing the case folded.

Fig. 5 is a vertical sectional view taken centrally and longitudinally through the case when folded.

Referring now to the drawings the present case comprises a bottom, rectangular pan 10, having the side walls 11 and 12 and the end walls 13 and 14 respectively, this pan, in practice, being preferably pressed from a sheet of metal. The side walls have each a series of spaced ears 15 that are bent into tubular form to constitute hinge members, the ears of each side receiving a pintle wire 16. Sides 17 and 18 are provided for

the case and each of which has a series of 55 ears 19 in spaced relation at its lower edge and which are bent into tubular form and alternate with the ears 15 so as to receive jointly with them, the corresponding pintle wire 16. Thus, are the sides 17 and 18 60 hinged to the pan sides.

The ends 13 and 14 of the pan have also each a series of spaced, upstanding ears 20, that are bent into tubular form to receive a pintle wire 21. Ends 22 and 23 are provided 65 for the case and each has a depending series of spaced ears 24 that alternate with the corresponding ears 20 and are bent into tubular form to receive the corresponding pintle wire 21. Thus are the ends 22 and 23 hinged 70 to the corresponding ends of the pan.

Disposed transversely of the bottom of the pan and mid-way of its ends, is an angle plate 25 having upwardly directed ears 26 that are in spaced relation and bent into 75 tubular form to receive a pintle wire 27 and a partition plate 28 has ears 29 depending from its lower edge and bent into tubular form and alternating with the ears 26 to receive jointly therewith the pintle wire, to 80 constitute a hinge connection between the partition plate and the angle plate which is secured to the bottom of the pan.

The end edge portions of the ends of the body of the case are turned outwardly at 85 right angles to engage within the open beads 30 that are bent inwardly from the end portions of the sides of the body, this engagement being effected by swinging the ends upwardly and outwardly and serving to limit 90 such movement when the ends are in vertical positions. To hold the ends from swinging inwardly, latch plates 31 are pivoted against their inner faces and have their free ends turned inwardly and at right angles as 95 shown at 32. Inverted L-shaped slots 33 are formed in the upper corners of the sides of the body of the case with the horizontal portions of the slots directed inwardly of the sides. The point of the metal within the 100 angle of each of these L-shaped slots, is deflected inwardly so that when the corresponding latch plate is swung downwardly, its laterally or inwardly directed portion 32 will pass through the horizontally directed 105 portion of the slot while the body of the latch will pass downwardly of the vertical portion of the slot and will wedge, so that

the end wall of the body of the case cannot swing inwardly. Similar slots 33' are formed near the upper edges of the sides of the body to receive similar angular latch 5 plates 34 that are pivoted to the partition near its upper edge, to prevent folding of the partition in one direction and to lock the partition to the side walls so that they may not be displaced outwardly at their 10 middle portions.

At the upper edge of each side 17 and 18 of the body of the case is formed an up-standing series of spaced tubular ears 35 that receive a pintle wire 36, about which 15 are engaged the tubular ears 37 formed at the outer longitudinal edges of the cover plates 38 and 39, the end portions of which are flanged downwardly as shown at 40, to engage against the outer faces of the ends of 20 the body of the case. The metal of each of the cover plates is struck downwardly, to form the circular bosses 41 and 42 respectively, one of which is slightly larger than the other to receive the other and through 25 the bottoms of these bosses are formed the slots 43 and 44 that register when the bosses are mutually engaged. The upper edge portion of the partition is cut away at each side of its middle portion to produce a 30 tongue 45 and when the cover plates are active, this tongue projects through the slots 43 and 44 to receive in its perforation 46 above the bottom of the uppermost boss, a seal or lock, thus to hold the case closed and 35 to positively position the partition.

Fillers of any desired style may be employed in the case or the case may be used without fillers, depending upon the character of the goods being shipped, and the dimensions of the pan are such as to permit of 40 packing of the fillers into it.

It will be noted that the angle plate to which the partition is hinged, is of lesser height than either end of the pan, while one 45 end of the pan is of lesser height than the other. This is in order that the members hinged thereto may fold readily into the pan, one above the other. Also, it will be noted than one side of the pan is higher 50 than the other, both being higher than the higher end of the pan, so that the sides of the body may fold one above the other, over the pan. When folded, the cover members lie upon their corresponding sides of the 55 body of the case.

It will be understood from the foregoing that there is provided a case of extreme durability, that will be rigid when set up and which when folded, will occupy a very small

space with resultant economy in return 60 freight.

What is claimed is:

1. A folding shipping crate having a closure member hinged to it and provided with an inwardly struck boss and a corresponding outer recess, the bottom of the recess having an opening through it and a wall of the crate having spaced notches and a resultant tongue disposed to project through said opening and lie within the recess of the 70 boss when the closure member is in a closed position and the notches being proportioned to receive the boss with the closure upon the wall, the tongue terminating flush with the upper edge of its wall and being adapted to 75 receive a retaining device for the closure member, exterior to said member.

2. A folding shipping case in which a foldable side wall is provided with an inverted L-shaped slot with the metal bounding the slot within the angle of the L, deflected inwardly of the case, and a foldable end wall has a latch plate pivoted to it and having its free end portion turned laterally and removably engaged behind said deflected 80 metal of the side walls.

3. A folding shipping case comprising a bottom member, side and end walls hinged to the bottom member to fold thereover, a partition having hinge connection with the 90 bottom member to fold thereover, the side walls having each a series of slots including each a vertical and a laterally extending portion, the metal within the angle of the slot being deflected inwardly, angular latch 95 plates pivoted to the partition and the end walls respectively and having laterally directed end portions to engage behind the deflected metal of the side walls, respectively, the partition having an upwardly directed 100 and perforated tongue with a recess at each side, and a cover member hinged to each side wall and having a slotted boss struck therefrom with a corresponding exterior recess, the bosses being disposed to fit one within 105 the other and to receive in their slots the tongue of the partition with its free end within the recess of the outer boss when the case is set up, the perforation of the tongue being disposed to receive a locking element 110 above the corresponding recess bottom.

In testimony whereof, I affix my signature, in the presence of two witnesses.

GEORGE C. PARKER.
